LITTER RECEPTACLE

Eleanor V. Kingsley, 490 Preciad St., Pomona, Calif.

Filed Apr. 5, 1965, Ser. No. 84,609

Term of patent 14 years

(Cl. D58—17)

FIGURE 1 is a front perspective view of a litter receptacle showing my new design, it being understood that the decoration partially indicated on the front, rear and two sides extends over the entire surface thereof;

I claim:

The ornamental design for a litter receptacle, as shown and described.
